UNITED STATES PATENT OFFICE.

MORDUCH L. KAPLAN, OF BROOKLYN, NEW YORK, ASSIGNOR TO BEACON MINIATURE ELECTRIC CO., INC., OF NEW YORK, N. Y., A CORPORATION OF NEW YORK.

FLASH-LIGHT.

1,178,928.

Specification of Letters Patent. Patented Apr. 11, 1916.

Application filed November 24, 1914. Serial No. 873,696.

To all whom it may concern:

Be it known that I, MORDUCH L. KAPLAN, a citizen of the United States, and a resident of Brooklyn, in the county of Kings and 5 State of New York, have invented certain new and useful Improvements in Flash-Lights, of which the following is a specification.

The invention pertains more particularly 10 to portable electric lamps of the character designed to be held in the hand and sometimes used as flash lights and at other times for affording a permanent light for a short period, and the object of the invention is to 15 provide a novel and efficient construction of lamp of the class referred to by which certain advantages are attained, one advantage being the avoidance of locating the movable circuit closer switch on the outside of the 20 tubular casing.

It is customary in the class of flash lights to which my invention pertains to provide a box-like escutcheon on the exterior of the tubular shell or casing and to mount on this 25 escutcheon a slide having inwardly projecting fingers engaging a movable circuit closer located within the box-like portion of the escutcheon, and by means of my invention the box-like portion of the escutcheon 30 is dispensed with and in lieu thereof I am enabled to use simply a flat plate escutcheon to receive the slide by which the circuit closer is operated.

My invention comprises, in a lamp of the 35 class referred to, a main shell or casing having within its wall a through opening of sufficient width and length to receive and permit the operation of a circuit closing switch, a flat escutcheon plate closing the 40 outer side of said opening, and a slide mounted on said plate and connected with the circuit closer switch in said opening.

The invention will be fully understood 45 from the detailed description hereinafter presented, reference being had to the accompanying drawings, in which:

Figure 1 is a side elevation of a portable electric light embodying my invention; Fig. 2 is a central vertical section, on a larger 50 scale, of the same, on the dotted line 2—2 of Fig. 1; Fig. 3 is a horizontal section through the casing of the flash light and the circuit closer mechanism taken on the dotted line 3—3 of Fig. 2; Fig. 4 is a detached inner face view of the escutcheon plate carry-

ing the circuit closer switch, and Fig. 5 is a detached outer face view of the escutcheon plate, the circuit closer features being omitted.

In the drawings 10 designates the exterior 60 casing or shell, 11 the battery therein, 12 the customary metal cap closing the lower end of said casing or shell, 13 the lens, 14 the reflector, 15 the usual cap or ring applied to the forward end of the casing or shell 65 and holding the lens and reflector in position, and 16 the lamp bulb having a socket 17 screwed into a neck 18 of said reflector, one terminal of the lamp being in engagement at 19 with the forward end of the battery and the rear or lower end of the battery being in engagement with the conducting spring 20 which is in electrical connection with the cap 12. The cap 12 is screwed upon a metal band 21, and this band is in electrical connection with a conducting strip 22 70 extending along the inner wall of the casing or shell 10. The cap or ring 15 is screwed upon a metal band 23 which is in electrical connection with the reflector 14 and also 75 with a conducting strip 24 which extends along the inner wall of the casing or shell 10. All of the features which have been enumerated by reference numerals are known features in flash lights and hence require no specific description.

The shell or casing 10 is of non-conducting material and preferably formed of vulcanized fiber, and this casing or shell 10 is, in accordance with my invention, formed 90 with an opening or hole 25 which is permanently open at its inner side and closed at its outer side by the application to the shell or casing 10 of a flat escutcheon plate 26, this plate being of metal and preferably 95 of ornamental outline and being secured to the casing or shell 10 by means of eyelets 27, 28, the eyelet 27 serving to secure the forward end of the conductor 22 with the metal plate 26 and place said conductor and 100 plate in electrical connection with each other.

The forward end of the escutcheon plate 26 extends over and conceals an eyelet 29 by which the lower or rear end of the conducting strip 24 is secured to the wall of the shell or casing 10. The conductor 22 is located at one side of the longitudinal plane of the opening or hole 25, and the conductor 24 is in direct line with said open- 110

ing and at its lower or rear end terminates at the forward edge of the opening 25.

Upon the escutcheon plate 26 is mounted a thumb-piece or slide 30 having side fingers 31 which project through parallel longitudinal slots 32 formed in the escutcheon plate 26 and are bent over laterally toward each other upon the circuit closer switch 33, which is a metal plate applied against the inner face of the escutcheon plate 26 and is recessed at its opposite edges to receive the fingers 31. The fingers 31 coöperating with the recesses in the edges of the circuit closer plate 33 serve to firmly connect said plate with the thumb-piece or slide 30 and to bind the plate 33 with sufficient firmness against the inner face of the plate 26. The fingers 31 coöperating with the slots 32 in the plate 26 serve to guide the thumb-piece 30 and plate 33 in their sliding movements. The plate 33 in its rear portion has a plain surface adapted to the inner face of the escutcheon plate 26, and forwardly of the fingers 31 the plate 33 is bent inwardly and then deflected forwardly, as at 34, the forwardly deflected portion of the plate 33 being slightly inclined laterally so that its forward extremity, when the plate 33 is pushed forwardly, may pass into electrical engagement with the inner or rear end of the conducting strip 24, thereby to complete the circuit through the lamp and battery. It will be seen that the casing or shell 10 is of adequate thickness to provide an opening or hole 25 within which the circuit closer switch 33 may be conveniently housed, and one of the purposes of my invention is to house the circuit closer switch within an opening 25 in the side of the casing 10 in lieu of having said switch housed in a box-formation mounted upon the exterior of the casing 10 or located within the chamber formed by the inner wall of the shell or casing 10. The opening 25 is of sufficient length to permit the thumb-piece 30 and circuit closer switch 33 to be moved from the inoperative position of said switch plate, shown in Fig. 2, forwardly to the operative position of said plate 33, such movement carrying the deflected end portion 34 of the plate 33 into electrical engagement with the inner end of the conducting strip 24. A reverse movement of the thumb-piece 30 will carry the plate 33 out of engagement with the conducting strip 24, and hence on such movement the circuit will be broken. The flat escutcheon plate 26 will lie close to the exterior surface of the shell or casing 10 and receive the thumb-piece 30, the latter being projected outwardly only far enough to enable its convenient operation by means of the thumb. In many known constructions an escutcheon plate is made use of having a projecting box-like portion which receives the circuit closer switch and has

mounted on its exterior the thumb-piece or slide, all this making a construction which projects unduly from the side of the flash light and not only mars the appearance of the flash light but is liable to be knocked and disfigured or broken during the handling of the flash light or when said light may, for instance, be carried in a box of tools by a mechanic. In accordance with my invention the circuit closer switch is confined within the opening 25 and the escutcheon plate 26 is simply a flat plate having no projecting or box-like portion but closely engaging the surface of the shell or casing 10 and conveniently receiving a thumb-piece or slide which in practical use will project only to the necessary extent beyond the outer face of said plate.

What I claim as my invention and desire to secure by Letters Patent, is:

1. A portable flash light comprising a casing of insulating material, a battery therein, an electric lamp having one terminal in engagement with one end of said battery, normally separated conductors extending along said casing from the other terminal of the lamp and the other end of said battery respectively, and circuit closer means for electrically connecting adjacent portions of said conductors and completing the lighting circuit, said casing having in its side wall adjacent to the inner ends of said conductors a hole forming a chamber in said wall, and said circuit closer means comprising a slideable switch located within said chamber and electrically connected with one of said conductors and having a free end to be engaged with the other of said conductors, an escutcheon plate secured on said casing closing the outer end of said chamber and a slide mounted on said plate and having a member extended through an elongated slot therein and rigidly engaged with said switch, whereby the switch may be slid into engagement with said other conductor to complete the circuit, said slide being elongated to conceal the slot in said plate and said slot and said member coöperating to guide said slide in its movements.

2. A portable flash light comprising a casing of insulating material, a battery therein, an electric lamp having one terminal in engagement with one end of said battery, normally separated conductors extending along said casing from the other terminal of the lamp and the other end of said battery respectively, and circuit closer means for electrically connecting adjacent portions of said conductors and completing the lighting circuit, said casing having in its side wall adjacent to the inner ends of said conductors a hole forming a chamber in said wall, and said circuit closer means comprising a slideable switch located within said chamber and electrically connected with one

of said conductors and having an inwardly bent free end to be engaged with the other of said conductors at the edge of said chamber, an escutcheon plate secured on said casing closing the outer end of said chamber and a slide mounted on said plate and having a member extended through an elongated slot therein and rigidly engaged with said switch, whereby the switch may be slid into engagement with said other conductor to complete the circuit, said switch being in permanent electrical connection with said plate and said plate being in permanent electrical connection with one of said conductors and these being the means for electrically connecting said switch with said conductor, and said slide being elongated to conceal the slot in said plate and said slot and said member coöperating to guide said slide in its movements.

3. A portable flash light comprising a casing of insulating material, a battery therein, an electric lamp having one terminal in engagement with one end of said battery, normally separated conductors extending along said casing from the other terminal of the lamp and the other end of said battery respectively, and circuit closer means for electrically connecting adjacent portions of said

conductors and completing the lighting circuit, said casing having in its side wall adjacent to the inner ends of said conductors a hole, and said circuit closer means comprising a switch located within said hole and electrically connected with one of said conductors and having an inwardly bent end to be engaged with the other of said conductors at the edge of said hole, an escutcheon plate secured on said casing closing the outer end of said hole and having parallel guide slots therein, and a slide mounted on said plate having side fingers extended through said slots and bent over on said switch for securing the switch to the slide and binding the switch against the inner surface of said plate, whereby the switch may by pressure on the slide be moved into engagement with said other conductor to complete the circuit, said plate serving as the means for permanently electrically connecting the switch with the first conductor.

Signed at New York, in the county of New York and State of New York, this 23rd day of November, A. D. 1914.
